UNITED STATES PATENT OFFICE

151,981

DESIGN FOR A COMBINED AIR TRAVEL BAG AND COSMETIC CASE

Elizabeth N. Graham, New York, N. Y.

Application January 8, 1948, Serial No. 143,589

Term of patent 14 years

(Cl. D87—3)

To all whom it may concern:

Be it known that I, Elizabeth N. Graham, a citizen of the United States of America, residing in New York city, county of New York, and State of New York, have invented a new, original, and ornamental Design for a Combined Air Travel Bag and Cosmetic Case, of which the following is a specification, reference being had to the accompanying drawing, forming part thereof, wherein:

Figure 1 is a front elevational view of a combined air travel bag and cosmetic case showing my new design with the front flaps in closed position concealing the cosmetic case.

Figure 5 is an additional front elevational view thereof with the flaps in open position to disclose the cosmetic case.

I claim:

The ornamental design for a combined air travel bag and cosmetic case, substantially as shown and described.

ELIZABETH N. GRAHAM.
